UNITED STATES PATENT OFFICE.

CHARLES H. DESAUTELS, OF SPRINGFIELD, MASSACHUSETTS, ASSIGNOR TO THE FISK RUBBER COMPANY, OF CHICOPEE FALLS, MASSACHUSETTS, A CORPORATION OF MASSACHUSETTS.

BEAD COVERING.

Application filed June 6, 1923. Serial No. 643,610.

This invention relates to improvements in methods and apparatus for covering articles such as tire bead fillers with a material such as rubberized fabric. It is particularly directed to the wrapping of clincher bead fillers with a covering of fabric adapted to project beyond the filler and form a so-called "suspension" which may lie between the carcass plies of the built-up

10 tire casing.

It has for its object the provision of a method and apparatus which will shape the fabric smoothly, tightly, and evenly about the bead filler, which is particularly adapted for handling beads in endless form, and which will in a single and simple operation completely shape a single piece of fabric to the desired form.

The invention will now be described in connection with the accompanying drawings, in which

Fig. 1 is a top plan view of the machine; Fig. 2 is a front elevation thereof; Fig. 3 is an elevation from the right in

25 Fig. 2;

Fig. 4 is a section on line 4—4 of Fig. 1; Fig. 5 is a detail rear elevation; Fig. 6 is a similar view showing the parts in a different operative position;

30 Fig. 7 is a fragmentary view similar to Fig. 2 but on an enlarged scale;

Fig. 8 is a section on line 8—8 of Fig. 7; Fig. 9 is a section on line 9—9 of Fig. 7; Fig. 10 is a section on line 10—10 of

35 Fig. 7;

Fig. 11 is a section on line 11—11 of Fig. 7;

Fig. 12 is a section on line 12—12 of Fig. 1;

40 Fig. 13 is a section on line 13—13 of Fig. 7;

Fig. 14 is a section on line 14—14 of Fig. 7;

Fig. 15 is a section on line 15—15 of Fig. 7;

Fig. 16 is a section on line 16—16 of Fig. 7;

Fig. 17 is a section on line 17—17 of Fig. 7;

50 Fig. 18 is a section on line 18—18 of Fig. 7;

Fig. 19 is a section on line 19—19 of Fig. 7;

Fig. 20 is a fragmentary section of a bead

of a finished tire, showing the covered bead 55 in place;

Fig. 21 is a perspective view similar in extent to Fig. 7, showing the passage of the bead and covering material through the apparatus; and

Fig. 22 (Sheet 2) is a section corresponding to Fig. 19 but showing a slightly different form of bead.

In some forms of clincher tire casings the bead or bead filler *a* (Fig. 20) is covered 65 with a strip of fabric *b*, the sides of which extend at *c* between the plies of the tire carcass. It is desirable that this covering material be pressed smoothly and firmly 70 into contact with the bead at all points, and with the edges of the fabric accurately offset the desired amount from each other and from the bead. The present invention is particularly intended to be employed in the placing of this so-called "flipper-strip" or 75 "suspension" around clincher beads; but may find utility in other connections, as applying a fabric covering without the extension *c*. The method of treating the bead and fabric which forms part of the invention can best be described in connection 80 with the machine designed for carrying it out.

The mechanism is supported on a table frame 25 upon which are fixed journal boxes 85 26 for a series of three shafts 27, 28, and 29, mounted substantially in line with each other horizontally, but preferably with shaft 29 disposed slightly lower than and out of line with the other two. This makes easier 90 the construction of the driving mechanism for the shafts, and also serves an additional purpose which will appear below. Suitable sprockets are provided on the shafts over which pass a chain 30, by means of 95 which all the shafts are simultaneously driven. One of the shafts, 28 as shown, has a second sprocket, over which runs a chain 31 passing over a sprocket on the shaft of a motor 32. By this means the three shafts 100 may receive simultaneous power rotation as desired, suitable clutch or switch devices being provided to place the control of the rotation under the control of the operator. As 105 a simple electrical switch will suffice it has not been illustrated in order not to confuse the showing of the other features of construction.

Pivoted at 33 between standards indicated at 34 are arms 35, 36, and 37, extending over shafts 27, 28, and 29 and carrying freely journaled at their ends rolls 38, 39, and 40, adapted for cooperation in a manner to be described with rolls 41, 42, and 43, fixed to the ends of the three shafts mentioned. Springs 44, mounted in caps 45 on a standard 46, constantly press the rolls of the upper set individually against the corresponding lower roll with a yielding pressure. It will be noticed that roll 40 is disposed to one side of its lower roll, for a purpose which will appear.

The arms 35, 36, and 37 extend rearwardly or away from their roll ends, and are connected by suitable operating means so that they may be depressed, thereby raising the rolls to free the work held between the upper and lower sets. In the case shown a link 47 is attached to the rear end of the center arm 36, and is connected at its lower end with a treadle 48 pivoted at 49 to the frame. By depressing the treadle the operator raises the rolls to permit of the insertion or removal of work from between the upper and lower sets of rolls. The middle arm has sidewardly extending projections 50 which overlie the two side arms and cause them to partake of the downward movement of the rearward extension of the middle arm. In order to permit each of the three arms to have a slight individual movement, assisting principally in permitting the passage through the rolls of a fabric splice or other enlargement of the work, a lost motion connection is provided between the middle and side arms, illustrated in Figs. 5 and 6. In Fig. 5 the arms are shown in their normal or operative position. It will be seen that a slight space 51 is provided between the side extensions 50 and the rear ends of arms 35 and 37. This permits the rear end of the arm 36 to be depressed independently as its forward end is raised by the passage of a splice. Arms 35 and 37 of course are free to move downwardly at their rear ends without any interference from the end of arm 36 or the side extensions 50.

The operation of the device may now be described, the remaining mechanical features and elements being considered in the order of their operation upon the bead to be covered. The machine has been designed with a particular intention of covering beads which have previously had their ends joined so as to form rings or hoops of the proper dimensions for incorporation into the tire. Beads in long lengths can be covered also if desired, and later formed into rings, but it is believed that more satisfactory results as to the strength of the splice will generally be obtained if the beads are first made endless.

The covering fabric *b* for the beads is sup-

plied on a roll 52 mounted at one end of the frame 25 in brackets 53. This fabric is generally light canvas or sheeting covered on one or both sides with rubber and cut on the bias so as to be extensible longitudinally with the bead of the clincher tire. In order to prevent undesired adhesion between adjacent turns of fabric in the roll it is wound between turns of a lining material *d* such as sheeting. This lining material passes over a roller 54 and is rewound on a spool 55 mounted in a bracket 56 and provided with a handle 57 or other rotating means. The covering material may be supplied in long lengths and severed as it is applied to the beads or may be cut to the proper length before being rolled up in the liner. In either case it is desirable to have the liner pass over the surface of frame 25 for a short distance as shown in Fig. 1 in order to give easy access to the covering material.

In order to guide the covering material accurately to the covering mechanism, overhanging side guides 58 (Figs. 1 and 8) are provided having guiding shoulders 59 spaced apart a distance substantially equal to the width of the fabric. I have found it desirable to reduce as much as possible the friction on the fabric as it enters the folding mechanism, and to this end provide rollers 60, journaled at 61 in side members 58, and arranged to underlie the guides. The guide may be made to slide longitudinally in the frame if desired so as to afford space for the severing of the covering material at a point near its contact with the bead, but the fixed construction shown is satisfactory where the covering material is supplied in strips cut to length.

The bead filler *a* is preferably guided into the folding mechanism from a point to one side of the line of travel of the fabric, as this permits the use of circular beads. The first guide which receives the bead is composed of two rollers 62 set in V formation on pins 63 supported by a bracket 64 (Figs. 1 and 12). The rollers are set so that their plane is oblique to the line of travel of the fabric, and also is tilted slightly outwardly from the vertical so that they will receive in a normal manner, between them, a bead which is supplied from below and one side of the fabric. Adjacent the entrance to the folding mechanism is a second V-shaped bead guide (Fig. 8) formed by rollers 65, suspended by headed pins 66 from brackets 67 attached to the top of the frame 25. This guide is arranged with the plane of the rollers vertical and at right angles to the line of travel of the fabric, and is preferably so located as to support the bead with its apex directly above the place on the fabric with which it is to contact.

This latter bead guide is preferably placed as close as convenient to the first pair of

rolls 38 and 41, so that accurate registry of the bead and fabric will be assured. Roll 41 has a shallow notch 68 adapted to receive the apex of the bead filler (Fig. 9), and has a flat cylindrical surface 69 supporting the fabric strip. Upper roll 38 is rounded on its periphery to conform to the shape of the concave side of the bead. In the folding of fabric around a bead to form a suspension 10 or flipper it is of particular importance to have accurate registry between the bead and fabric, for the reason that the fabric should extend beyond the bead filler between the plies of the tire carcass a uniform and definite amount, and the stepping off of the two edges of the covering fabric (see Fig. 20) should likewise be even. This condition can only arise if the bead and fabric are accurately registered at the inception of the 20 covering operation, for inaccuracies then cannot be corrected at a later stage. Rolls 38 and 41 serve as an effective insurance that accurate register of the bead and fabric is initially obtained, by pressing the fabric firmly into place in a small area around the apex of the bead. By restricting the initial application of fabric to a small area the alignment is improved and errors due to the fabric contacting first with the wrong 30 part of the bead avoided.

As the bead and fabric pass from this pair of rolls to the next pair the fabric is acted upon by devices adapted to insure an even turning during the subsequent shaping around the concave base of the filler. I have found that the side of the fabric which is not to be folded over the base requires little attention, but that care must be taken with the side indicated by 70 in order to prevent wrinkles and creases. As this side leaves the first pair of rolls it is picked up by a small roller 71 (Fig. 10), carried by a pin 72 secured to a bar 73 and preferably arranged to contact with the apex of the 40 filler, the bar being mounted on the top of table 25. Following this the fabric contacts with one or more similar rollers 74 arranged at progressively steeper angles so as to carry the fabric gradually to the position of Fig. 50 11. Here it contacts with a roller 75 also mounted on bar 73 and slanted upwardly in the direction of travel and away from the side of the sheet, as shown, so as to lie more nearly at right angles to the direction of travel of the constantly turning side portion of the advancing fabric. The angular mounting of this roller is a safeguard acting to prevent any mistravel of the sheet edge and secure a neat and accurate folding. 60 From this last-named roller the material passes directly into the bite of rolls 39 and 42. The lower of these is shaped to conform with the two sides of the triangular bead adjacent its apex, and the upper roll, 65 similarly to roll 38, fits into the convex base

of the bead. As the fabric has been shaped by the intermediate rollers, roller 42 has practically no shaping to do on the side 70 of the strip, but does act to conform the opposite side 76 of the strip to the bead. As the rollers are firmly sprung pressed together, the fabric and bead will be thoroughly joined. If desired a guide piece 77 (Fig. 13) may be arranged to underlie the edge 70 and prevent any mistravel during the passage of the bead between these rolls. 75

As soon as the partially covered bead leaves the bite of rolls 39 and 42 the side 70 of the fabric comes into contact with a roll 78, the action of which is illustrated in Fig. 14. Successive rolls of the same series, numbered from 79 to 82, appear in Figs. 15 to 18. It will be noted that all of these rolls (with the exception of roll 78 which has only a preliminary guiding function) bear against the corner 83 of the bead filler and gradually and progressively turn the fabric over the concave base of the bead. This arrangement of rolls is preferred as I have found that a much tighter wrap is secured than if the fabric were not held positively in contact with the corner of the bead. These rolls are supported on pins 84 attached to a suitably bent bar 85, supported from arms 36 and 37 so as to be raised with the upper set 90 of rolls clear of the bead to be removed or positioned. 95

One important aspect of the invention may now be considered which is especially useful in cases where a strip of bias cut fabric is being wrapped around a bead having a concave base. Particularly in cases where the beads are made endless before covering with fabric there has been experienced much difficulty in making the suspension fabric lay evenly and tightly around the bead. I have found that by keeping the bead substantially straight while the fabric is folded around the apex and adjacent sides of the bead and until that portion of the fabric which is to cover the concave base is turned so as to overlie the base, and then curving the bead, the fabric will be drawn to the bead shape, and can be pressed easily into final position. As will be apparent from the drawings the first two pairs of pressing rolls are in line, and the rolls of each pair vertically arranged, while rolls 40 and 43 are arranged with the former to one side of the latter. In Figs. 7 and 21 the effect of this arrangement in bending the bead is clearly shown. 105 110 115

Although the maximum bending of the bead does not occur until it reaches the bite of rolls 40 and 43, the drawing tendency on the fabric of this flexing of the bead causes the overlying edge 70 of the fabric to gradually assume the curved shape of the bead base as it passes by the series of guiding and turning rollers shown in Figs. 14 to 18. By the time the fabric reaches roll 40 it has be- 120 125 130

come curved so that only a slight pressure is necessary in order to cause it to conform and adhere to the convex base of the bead.

The shape of roll 43 is much like that of roll 42, except that it has a ledge 86 at one side of the bead receiving cavity 87 slightly higher than the corner 88 of the bead. Roll 40 is like the corresponding roll 39, but is curved at 89 and 90 to give firm contact with the entire upper surface of the bead. At one side of roll 40 is a cylindrical extension 91, made separately rotatable in the case of easily distorted fabrics, which presses on the projecting fabric portions 70, 76, and causes the two layers to adhere firmly together. Ledge 86 is located higher than the corner of the bead since I have found that with the bend in the fabric made at this point no difficulty is experienced when the extension is later straightened out in line with the side of the bead as shown in Fig. 20, while if the bend were made close to the bead corner the rigidity at this point would cause a kink in the fabric when straightened.

25 The form of the bead receiving roll cavities may be varied, and the arrangement of the other parts changed to accommodate beads of other designs. Thus in Fig. 22 is illustrated a bead having one rounded side 92, the roll being shaped accordingly. As a preferable condition of operation of the mechanism described roll 43 is driven at a very slightly higher speed than the two preceding rolls 41 and 42, so that the bead and fabric at this point are kept taut. This difference in speed is slight, and can be most easily attained by a slight increase in the diameter of roll 43 as compared with roll 42.

40 The manner of operating the device will in the main be apparent from what has been said. The upper rolls of the three sets are raised by depressing treadle 48, and the bead placed in position. The fabric is unwound from spool 52 and started through the bite of rolls 38 and 41. The motor is then started, or the clutch mechanism actuated, and the wrapping of the bead will be completed in a single passage through the machine.

Having thus described my invention, I claim:

15 1. A method of covering with a strip of bias fabric a bead substantially triangular in form with a concave base portion, which comprises folding the fabric strip around the apex and adjacent side of the bead with the side of the fabric extending over the concave base of the bead, the bead being kept substantially straight during these operations, and flexing the bead to draw the fabric into the concave portion of the bead.

60 2. A method of covering with a strip of bias fabric a substantially triangular bead with a concave base portion, which comprises folding and pressing the fabric strip around the apex and one adjacent side of the bead

with the side of the fabric extending loosely over the concave base of the bead, the bead being kept substantially straight longitudinally, flexing the bead to draw the fabric into the concave side of the bead, and pressing the fabric firmly into the concave portion of the bead.

70 3. A method of covering with a suspension strip of bias fabric a substantially triangular bead with a concave base portion, which comprises pressing the strip of fabric against the apex of the bead, folding and pressing the side portions of the fabric against the sides of the bead with one side portion extending loosely over the concave base portion of the bead, the bead being kept substantially straight longitudinally, flexing the bead to draw the fabric into the concave portion of the bead, pressing the fabric into the concave portion of the bead, and pressing together the side portions of the fabric extending together beyond the bead.

75 4. A method of covering a substantially triangular bead which comprises folding a strip of fabric from the apex over one side of the bead while the bead is kept straight, the fabric overlying the base of the bead, and flexing the bead with the base outward to cause the fabric to conform to the base of the bead.

80 5. A bead covering machine comprising a plurality of pairs of rotatable pressing rolls, and intermediate fabric turning guides between successive pairs, said pairs of rolls being so disposed relatively to each other 90 that the bead is first caused to travel in a substantially straight path and is then flexed to draw into shape a portion of the turned fabric.

85 6. A covering machine for triangular 105 beads comprising a circumferentially notched roll adapted to receive the apex only of the bead, a pressure roll coacting therewith adapted to join to the bead a strip of covering material at the apex only of the bead, 110 and mechanism for shaping to the bead the fabric so attached.

90 7. A covering machine for triangular beads comprising a circumferentially notched roll adapted to receive the apex only of 115 the bead, a pressure roll coacting therewith, a guide adapted to supply to said rolls in properly aligned relation a strip of covering fabric, a guide adapted to supply a bead to said rolls, and mechanism for shaping to the bead the fabric attached to the apex thereof by said rolls.

95 8. A covering machine for endless triangular beads comprising a circumferentially notched roll adapted to receive the apex 125 only of the bead, a pressure roll coacting therewith, a guide adapted to supply to said rolls in properly aligned relation a strip of covering material, and guiding devices adapted to receive an endless bead from one 130

side of the covering strip, deflect it, and present it with its apex aligned with the notch of the roll.

9. A covering machine for triangular beads comprising a pair of pressure rolls adapted to unite the apex only of a triangular bead with a strip of covering fabric, a series of rollers adapted to turn one side of the fabric up the side of the bead, a second pair of pressure rolls adapted to press the covering fabric against the sides of the bead adjacent the apex, a second series of rollers adapted to contact with one base corner of the bead and set at progressively increasing angles to gradually turn one side of the fabric over the base of the bead, and a third pair of pressure rolls having their line of centers set at an angle to the line of centers of the preceding pair of rolls to cause the bead to be flexed with the base thereof outwardly disposed and adapted to press against the base of the bead the fabric previously turned thereover and to unite the edge of this fabric with the other side portion of the fabric.

10. A covering machine for triangular beads comprising a pair of pressure rolls adapted to unite the apex only of a triangular bead with a strip of covering fabric, a series of rollers adapted to turn one side of the fabric up the side of the bead, a second pair of pressure rolls adapted to press the covering fabric against the sides of the bead adjacent the apex, a second series of rollers adapted to contact with one base corner of the bead and set at progressively increasing angles to gradually turn one side of the fabric over the base of the bead, and a third pair of pressure rolls having their line of centers set at an angle to the line of centers of the preceding pair of rolls to cause the bead to be flexed with the base thereof outwardly disposed and adapted to press against the base of the bead the fabric previously turned thereover.

11. A covering machine for triangular

beads comprising a pair of pressure rolls adapted to unite the apex only of a triangular bead with a strip of covering fabric, a series of rollers adapted to turn one side of the fabric up the side of the bead, a second pair of pressure rolls adapted to press the covering fabric against the sides of the bead adjacent the apex, a second series of rollers adapted to contact with one base corner of the bead and set at progressively increasing angles to gradually turn one side of the fabric over the base of the bead, a third pair of pressure rolls having their line of centers set at an angle to the line of centers of the preceding pair of rolls to cause the bead to be flexed with the base thereof outwardly disposed and adapted to press against the base of the bead the fabric previously turned thereover, and means for positively driving the three pairs of pressure rolls with the third pair rotating at a slightly higher speed than the other.

12. A covering machine for triangular beads comprising a pair of pressure rolls adapted to unite the apex only of a triangular bead with a strip of covering fabric, a series of rollers adapted to turn one side of the fabric up the side of the bead, the last roller of the series being set at an angle extending outwardly and upwardly with respect to the line of travel of the bead, a second pair of pressure rolls adapted to press the covering fabric against the sides of the bead adjacent the apex, a second series of rollers adapted to contact with one base corner of the bead and set at progressively increasing angles to gradually turn one side of the fabric over the base of the bead, and a third pair of pressure rolls having their line of centers set at an angle to the line of centers of the preceding pair of rolls to cause the bead to be flexed with the base thereof outwardly disposed and adapted to press against the base of the bead the fabric previously turned thereover.

CHARLES H. DESAUTELS.
